MACHINE FOR MIXING CONCRETE AND
OTHER GRANULAR MATERIALS

Norman Harrison, Low Fell, England

Application February 21, 1934, Serial No. 712,422
In Great Britain January 21, 1933

2 Claims. (Cl. 83—73)

This invention relates to machines for mixing concrete and other granular materials of the kind comprising a rotary mixing pan having a central discharge door in the bottom of the pan.

5 The invention has for its object to provide means for effecting the rapid discharge of the mixing pan.

According to the invention a deflector plate is arranged to extend from the wall of the pan to 10 the edge of the central opening, the said plate being mounted so that it may be raised from the bottom of the pan while mixing is in progress. Preferably means for raising the plate are combined with the means for opening the central discharge door so that the plate comes down into 15 position when the door is opened.

The invention will now be described by way of example with reference to the accompanying drawings which show a portion of a concrete mixer 20 comprising means for opening the discharge door at the same time that the deflector plate is lowered.

In the said drawings:

Fig. 1 is a plan view.

25 Fig. 2 is a side elevation.

Fig. 3 is an end elevation.

Referring more particularly to the drawings, 1 is the mixing pan, and 2 the discharge door which is of the kind comprising a rotatable closure member mounted on an arm 3 which in its turn is mounted on a shaft 4 extending to the side of the machine frame, the outer end of the shaft 4 having an arm 5 which when the door 2 is in the closed position is in a substantially horizontal 30 position, a weight 6 on the arm 5 maintaining the door closed. To ensure the arm 5 remaining in the open position it is connected by lost motion means with the arm 3 so that when the door is opened the arm 5 is well past the vertical centre 35 line. On the outer end of the said transverse shaft 4 a second arm 7 is mounted and is connected by a connecting rod 8 and a universal joint 9 to the outer end of a lever 10 having its fulcrum on a frame 11 extending over the mixing pan 1. The said frame 11 has provided thereon four vertical bearings 12 through which pass two rods 13 which at their upper ends are secured to a horizontal member 14 connected at its mid-point to the inner end of the lever 10, while at

their lower ends the rods 13 are rigidly secured to a deflector plate 15.

The deflector plate 15 is concave with respect to the direction of rotation of the pan and is at an angle of substantially 45° to the latter. The inner end of the plate 15 is curved more sharply to ensure the material being carried well over the edge of the opening while discharge is taking place.

5 The connections between the lever arm 10 and the arm 7 are such that when the arm 5 is raised to open the door the lever 10 is rocked to bring the deflector plate 15 into position at the bottom of the pan as shown in chain lines; while when the door 2 is closed the lever 10 is rocked to raise 15 the deflector plate 15 off the bottom of the pan to such a height shown in dotted lines that it will clear the material in the pan 1.

I claim:—

1. In a machine for mixing concrete and other 20 granular materials of the kind described, comprising a rotary mixing pan having a central opening, a deflector plate extending from the wall of the pan to the edge of the central opening, a shaft extending to the side of the machine, a closure 25 member for said opening mounted on said shaft, an arm on said shaft, a lever, a connecting rod and universal joint connecting said arm to the outer end of said lever, vertically slidable rods in the mixing pan, said rods carrying at their lower 30 ends the deflector plate and a pivotal connection between the inner end of said lever and said vertical rods, the arrangement being such that the deflector plate is raised when the closure member is closed.

35 2. In a machine for mixing concrete and other granular materials of the kind described, comprising a rotary mixing pan having a central opening, a deflector plate extending from the wall of the pan to the edge of the central opening, a door 40 for closing said central opening, means for actuating said door, and means interconnected with said door actuating means so that when the door is actuated to open the central opening, the deflector plate is moved to the bottom of the pan, and 45 when the door is actuated to close the said central opening, the deflector plate is raised from the bottom of the pan.

NORMAN HARRISON.
